UNITED STATES PATENT OFFICE.

ANDREW A. COOK, OF IRWIN, PENNSYLVANIA, ASSIGNOR TO NATIONAL ELECTRIC SHOE SHINING MACHINE COMPANY, OF PITTSBURGH, PENNSYLVANIA, A CORPORATION OF DELAWARE.

AUTOMATIC SHOE-SHINING MACHINE.

1,063,416.

Specification of Letters Patent. Patented June 3, 1913.

Application filed October 30, 1910. Serial No. 568,201.

To all whom it may concern:

Be it known that I, ANDREW A. COOK, a resident of Irwin, in the county of Westmoreland and State of Pennsylvania, have 5 invented a new and useful Improvement in Automatic Shoe-Shining Machines, of which the following is a specification.

This invention relates to shoe polishing machines, and more particularly to that type 10 of machine wherein rotary brushes are reciprocated longitudinally on the shoe for cleaning and polishing the sides thereof and also for cleaning and polishing the toes thereof.

15 The object of the invention is to provide a machine of this character of simple construction, less liable to get out of order, more durable and more easily and cheaply operated than prior machines for this purpose.

20 The invention comprises the construction and arrangement of parts hereinafter described and claimed.

In the accompanying drawings Figure 1 25 is a side elevation of the mechanism of the machine, the casing being omitted; Fig. 2 is a front elevation of the mechanism on the upright or back board; Fig. 3 is a plan view of the lower portion of the mechanism 30 showing the brush carriage in its rear-most position; Fig. 4 is a transverse section on the line 4—4, Fig. 3; Fig. 5 is a horizontal section of a portion of the same on the line 5—5, Fig. 1; Fig. 6 is a vertical section on the line 6—6, Fig. 3; Fig. 7 is a detail view 35 of the electric cut-out and operating means thereof; Fig. 8 is a diagrammatic view illustrating the air pump and the control valve; Fig. 9 is a perspective view of the 40 cam for moving the toe brushes, and Fig. 10 is a sectional view through one of the sprayers.

In the drawings the base of the machine is indicated at 1 and the standard or up-right at 2, these not being shown in detail, 45 as any form of base and standard will answer the purpose. The mechanism will be inclosed in a suitable casing as is common with this type of machine, but no part of 50 the casing has been illustrated.

Rising from the base are standards 3 which support suitable guides 4 on the forward end of which is the foot rest 5. Mounted on the guides 4 to reciprocate

thereon is the carriage or carrier 6 for all 55 of the brushes, one special feature of the present improvement consisting in having all of the brushes mounted upon a single reciprocating carriage or carrier, thereby simplifying the construction. 60

Rotatably mounted in a suitable bearing 7 on the base 1 is a longitudinal shaft 8 provided at its rear end with bevel pinion 9 for imparting rotation thereto. Splined to the shaft 8 is a sleeve 10 which is rotatable 65 in a bearing 11 depending from the carriage 6. Secured to the sleeve 10 is a pinion 12 which meshes on opposite sides with gears 13 and 14 secured respectively to shafts 15 and 16 also rotatably mounted in the de- 70 pending portion 11 of the carriage 6.

A brush is provided on each side of the foot rest to clean and polish the sides of the shoe, these brushes being marked 17 and 18, respectively, and are mounted on vertical axes 19 which are rotatable in bearings 20 in the outer ends of arms 21 which are pivoted to the carriage 6 on the vertical pivots 22. To the lower end of each brush spindle 19 is secured a bevel pinion 23 meshing with a similar pinion 24, said pinions 24 being connected with shafts 15 and 16, respectively, by means of flexible shafts 25 the outer ends of which are rotatable in bearings 26 in a depending portion of arms 80 21. By means of the gearing described the brushes 17 and 18 are positively rotated from the shaft 8. The flexible shafts 25 permit the brushes to swing toward and from each other on the pivots 22. A spring 85 28 connects the arms 21 and normally holds the brushes toward each other, or in the position shown in Fig. 3. As the carriage 6 is reciprocated these brushes pass along the sides of the foot rest, being spread apart 90 by contact with the shoe being polished, and again coming together at the heel of the shoe, as shown in dotted lines, Fig. 3.

The power for rotating shaft 8 and reciprocating the carriage 6 may be derived 100 from any suitable source. As shown, it is derived from an electric motor 30 mounted on the upright or standard 2 and having its armature shaft connected by belt 31 with a pulley on shaft 33. This shaft is connected by a suitable train of speed reducing gearing to a crank shaft 34, said train of gearing comprising a pinion 35 on shaft 33

meshing with gear 36 fast on countershaft 37 which carries a pinion 38 meshing with a gear 39 on countershaft 40, said last named countershaft carrying another pinion 41 meshing with a gear 42 on the crank shaft 34. All of the shafts described are mounted in suitable bearings in a web 43 projecting from the upright or standard 2. Any other suitable train of speed reducing gear-
ing may be employed.

The carriage 6 is reciprocated from shaft 34 by means of crank 45 on said shaft 34 and connected by link 46 to one arm 47 of a three-armed lever fulcrumed at 48 and whose arm 49 is connected by link 50 to the carriage 6 by bolt or pin 51. It is obvious that the rotation of crank 45 through the links and lever described imparts a reciprocating forward and backward motion to the carriage 6, to carry the brushes 7 and 8 alternately from the full line position shown in Fig. 3 to the dotted line position shown therein.

The shaft 8 is driven directly from shaft 33 through intermeshing bevel pinions 53 secured respectively to shaft 33 and to the upper end of a substantially vertical shaft 54 mounted in suitable bearings 55 on the standard or upright and at its lower end carrying a bevel pinion 56 which meshes with the bevel pinion 9 on the rear end of shaft 8. Consequently as the carriage 6 is reciprocated back and forth rotary movement is imparted to the brushes 17 and 18 by the sleeve 10 which is splined to the rotary shaft 8, as will be understood.

In my improved machine the toe or upper and forward part of the shoe is cleaned and polished preferably by a plurality of brushes, the drawing showing three brushes 60, 61 and 62, although two or more may be used. The first brush 60 is preferably formed of bristles and serves to clean the shoe, the second also is preferably of bristles and serves to brush the shoe after the application of the blacking, while the brush 62 is formed of felt or the like and constitutes the polishing buffer. These brushes are held in a frame comprising side or end pieces 63 and 64 and cross connecting rods or pieces 65 and 66. At the forward ends of the side pieces 63 and 64 are bearings 67 for a shaft 68 to which the brushes are splined so as to slide thereon and rotate therewith. The bearings 67 are also slideable on shaft 68, the latter being held against endwise movement by having its outer end mounted in bearing 69 on an arm 70 which is secured to a horizontal rod or bar 71 secured to the rear end of the carriage 6. Secured to shaft 68 is a bevel pinion 74 meshing with a similar pinion 75 having a shaft mounted in bearing 76 and connected by flexible shaft 77 to a short shaft mounted in bearing 78 in the lower end of bracket 79 depending from the

carriage 6, said short shaft being provided with a bevel gear 80 meshing with a similar gear 81 on the rear end of shaft 15. The toe brushes are therefore positively rotated from shaft 8 through the train of gearing described. The toe brushes are movable laterally with reference to the carriage 6 so as to bring the several brushes in succession into operative position with relation to the shoe being polished. To this end the cross rod 66 of the brush carriage or frame is slideable in bearings 83 on the rear ends of the arms or brackets 84 projecting rearwardly from carriage 6. The frame 63 is also provided with a downwardly projecting arm 85 carrying a roller 86 which travels on the rod or bar 71. The splined connection of the toe brushes with the shaft 68 permits of such lateral movement without breaking the connection for rotating said brushes.

The mechanism for moving the brush carriage or frame laterally comprises a cam wheel 87 rotatably mounted on a stud or spindle 88 carried by bracket 89 projecting laterally from the carriage 6. This cam wheel has projecting from its lower face a series of pins 90, the drawings showing six such pins. Secured to the base 1 is a standard 92 upon which is fulcrumed at 93 a relatively stationary cam 94, said cam 94 being free to rotate slightly on its fulcrum in the direction of the arrow 95 (Fig. 3), but being prevented from movement in the opposite direction by reason of its face 96 contacting with a portion 97 projecting upwardly from standard 92. A spring 98 holds the cam 94 normally in contact with stop 97. The cam wheel 87, as stated, is carried by carriage 6, and in the rearward movement of said carriage one of the pins 90, specifically, that which occupies the position so numbered in Fig. 3, passes inside or in front of the cam arm 94, as is apparent from Fig. 3, so that in the further return movement of said carriage 6 this pin is forced by the forward face of cam arm 94 to the position indicated at 99, Fig. 3, thereby imparting rotation to the cam wheel 87 through an arc of 60 degrees. Consequently, for six complete reciprocations of carriage 6 the cam wheel 87 makes one complete revolution. This cam wheel has the cam segment 100 extending through a semi-circle and elevated above its main body, and which in the rotation of the wheel 87 contacts with the end piece 64 of the brush frame and pushes the same laterally toward the right, viewing Fig. 3. The end of cam segment 100 which first contacts with the brush frame or carriage is preferably provided with a small vertical roller 101 to reduce friction. A spring pressed pawl 102 is carried by wheel 87 and cooperates with a stationary ratchet 103 to prevent backward rotation of the cam wheel.

The pins 90 and cam segment 100 are so

located and the segment is of such length as to allow of the necessary number of actions of the several brushes on the shoe, between lateral movements of the brush carriage. In the specific arrangement shown the pins 90 are so located that during the first two reciprocations of the carriage 6 the wheel 87 is in such position that the cam segment 100 does not contact with the brush frame or carriage and consequently during these two reciprocations the brush 60 acts upon the toe and front part of the shoe. At the next backward stroke of the carriage 6 the cam wheel 87 is given a rotary step through 60 degrees thereby causing the end roller 101 of the cam segment to push the brush frame or carriage laterally about one-half of its full travel, thereby bringing brush 61 in line with the shoe. This lateral shifting of the brush carriage occurs just after the blacking material has been sprayed thereon so that said brush 61 brushes off the excess blacking material. On the next backward stroke of the carriage 6 the cam wheel 87 is given a further rotary movement through 60 degrees, thereby turning the cam segment 100 sufficiently far to push the brush carriage fully over toward the right, viewing Fig. 3, thereby bringing buffer brush 62 in line with the shoe. The cam segment 100 is of such length that it holds the brush frame or carriage in its extreme right position through three reciprocations of the carriage 6, thereby insuring a good buffing action to polish the shoe. As soon as the end of cam segment 100 passes the frame member 64 the brush frame or carriage is retracted, or pulled fully to the position shown in Fig. 3, by means of a helical tension spring 105 connecting the end member 63 of said carriage or frame with one of the stationary arms 84 of carriage 6.

It will be apparent from the foregoing description that the carriage 6 has two complete reciprocations with the brushes 17 and 18 acting against the sides and heel of the shoe and brush 60 acting on the toe and front part of the shoe. At the end of the two reciprocations the blacking is sprayed onto the shoe by means hereinafter described, and the carriage then again moves forward and back with the brushes 17 and 18 acting against the sides and heel of the shoe and the brush 61 acting on the toe and front part of the shoe. During the next three reciprocations of the carriage the brush 62 acts on the toe and front part of the shoe, the sides and heel being acted on in all reciprocations by brushes 17 and 18.

60 The means for spraying the blacking on the shoe are as follows: On the base 1 are one or more vessels or tanks 108 for the blacking in a liquid form, and extending from these are spray pipes 109, one such pipe extending at each side of the foot rest

5 and provided with a plurality (preferably three) of spray nozzles 110 located at such height and directed in such direction as to spray the blacking upon the shoe being cleaned. Preferably also a pipe 111 connects the tanks 108 and is provided with nozzle 112 at the rear of the foot rest to spray blacking upon the heel of the shoe. The liquid blacking is forced from the spray nozzles by means of air pressure, this being supplied through a pipe or hose 113 connected to an air pump 114, and provided with branches 115 whose ends project into the nozzles 110 and form with the latter atomizers or sprayers of a well known type 60 acting on the ejector principle. The air pump 114 is trunnioned at 116 on the upright or standard 2 and has its piston operatively connected to a crank 117 on the end of primary driven shaft 33. The pump operates continuously, as will be apparent, but the blacking is to be sprayed onto the shoe only momentarily, namely, immediately after the second complete reciprocation of the brushes as heretofore described. Consequently in the connection between the pump and sprayers there is provided a suitable valve which normally closes the connection but which is momentarily opened at the proper time. This valve is shown at 118 mounted on the upright or standard 2 and having the pipe 113 connected to its outlet and a flexible pipe or hose 119 connecting its inlet with the discharge outlet of the pump 114. This valve may be of any suitable 65 type, being shown as a typical three way rotary or plug valve, the rotary member 120 having connected thereto an arm 121 to which is connected a spring 122 which normally holds said arm against stop 122a, in 70 which position the valve closes connection between the air pump and sprayers. To open the valve the rotary plug is provided with another arm 123 adapted at the proper time to be contacted by a projecting finger 75 or cam 124 on an intermittently rotated shaft 125, such contact serving to rotate the plug valve against the tension of spring 122 and momentarily open connection between the air pump and sprayers. Shaft 125 is 80 mounted in a bearing 126 in the web 43 of the standard or upright 2, and at one end is provided with a six-armed star wheel 127 arranged to be actuated by a finger 128 on the shaft 34 which carries the crank for imparting reciprocatory movement to the carriage 6. Obviously the shaft 34 makes one 85 rotation for each full reciprocation of carriage 6 and consequently the shaft 125 is given one forward step movement at each 90 reciprocation of said carriage. The finger or projection 124 is so located on shaft 125 that it opens the valve at the proper time, to wit, after the shoe has been cleaned and when it is ready to receive the blacking. 95

The shaft 125 also serves to stop the machine after the pre-determined number of reciprocations of the brushes, which in the present machine consists of six. To this end the shaft 125 is provided with another projection 130 adapted at the proper time to contact with a shoulder on lever 131 which is pivotally connected to the lower end of the switch blade 133, the outer being pivoted at 134 and normally held by spring 135 between the terminals 136. The projection 130 acting against lever 131 pushes the lower end of the switch blade out of contact with the terminals and stops the motor 30, as will be readily apparent. The outer end of lever 131 is provided with a projection 137 by means of which the lever 131 can be lifted out of engagement with the projection 130 to permit spring 135 to close the switch and start the machine. Projection 137 can be actuated either by hand or by a coin, the latter method being generally used. The particular form of means for delivering the coin to this lever is not a part 25 of the present invention and has not been illustrated.

The operation of the machine will be readily understood from the foregoing description, and briefly is as follows: After the user places his foot upon the foot rest 30 the lever 131 is disengaged from projection 130 by pressing down on the outer end 137 of said lever, thereby closing the electric switch and starting the motor. The latter 35 communicates rotary movement to shaft 33, and from the latter rotary movement is communicated through the shaft 54 and intermeshing gears to the lower horizontal splined shaft 8. Motion is also transmitted from shaft 33 through the train of reducing gearing to the crank shaft 34, and the latter by means of the crank 45, lever 47 and connecting rods 46 and 50 reciprocates the carriage 6 back and forth on the guides 4. 40 During this reciprocating movement the brushes 17, 18, and 60, 61 and 62 are constantly rotated from splined shaft 8 through the connecting gearing and flexible shafts described. The brushes 17 and 18 move 45 toward and from each other as they pass over the shoe, being held in constant contact therewith by spring 28, and meeting both in front of the toe and behind the heel, thereby perfectly cleaning and polishing the shoe. 50 At each reciprocation of the carriage 6 the cam wheel 87 is given one rotary step, and after the second reciprocation of the carriage moves the toe brush carriage or frame half way over, bringing the middle brush 55 61 in line with the shoe. At the end of the second reciprocation the air valve 118 is momentarily opened to spray the blacking onto the shoe. On the next backward reciprocation the cam wheel 87 is still further 60 rotated and pushes the supplemental car-

riage or frame entirely over toward the right, bringing the buffing or polishing brush 62 in line with the shoe, and during the further reciprocating movements of the carriage during the cycle, the cam wheel 87 holds the supplemental carriage in this position, but at the completion of the cycle of reciprocation, to wit, at the end of the sixth reciprocation, the cam frees itself from the supplemental carriage and the latter is pulled back to normal position by spring 105. At the end of the sixth reciprocation the electric switch is opened by cam projection 130 and the motor is stopped. 70

The necessary pressure of the side brushes 17 and 18 is secured by spring 28, although the flexible shafts 25 also tend to hold these brushes in contact with the sides of the shoe. The necessary pressure of the toe brushes is secured by gravity. The carrier or frame 35 for these brushes is practically pivoted on the rod 66, and the brushes are so positioned that as they pass over the shoe they are elevated, whereby practically the entire weight of the brushes, and their carrier and operating shaft is brought into play to press the brushes against the shoe. If desired, a tension spring may be added to pull downwardly on these brushes, although this has been found unnecessary. 95

The machine is of simple construction comprising comparatively simple trains of gearing, and all of the brushes and their immediate operating parts are carried by a single reciprocating carriage. In the simplest prior machines with which I am familiar it has required a reciprocating carrier for each of the said brushes 17 and 18, and a third carrier for the toe brush. In the present machine all of these are carried by the one carriage. On account of the simplicity of the machine it requires less power to operate, is less liable to derangement, and more reliable than prior machines for the same purpose. 105

Various modifications can be made in the arrangement of parts without departing from the invention. Especially is it possible to substitute different forms of connecting gearing for the train connecting shafts 33 and 34, and for the train connecting shafts 33 and 8. Other gearing than the trains including the flexible shafts 25 and 77 may be employed for rotating the brushes from longitudinal shaft 8. 115

What I claim is:

1. In a shoe shining machine, the combination of a foot rest, a horizontally reciprocating main carrier movable toward and from the foot rest, an auxiliary carrier mounted to move transversely on the main carrier, a plurality of toe-brushes mounted for rotation thereon, and mechanism for automatically moving said auxiliary carrier transversely of the main carrier. 125

2. In a shoe polishing machine, the combination of a foot rest, a horizontally reciprocating main carrier movable toward and from the foot rest, an auxiliary carrier mounted to move transversely on the main carrier, a plurality of toe-brushes mounted for rotation thereon, cam mechanism for automatically moving said auxiliary carrier step-by-step transversely of said main carrier, and a spring arranged to return said auxiliary carrier to normal position.

3. In a shoe polishing machine, the combination of a foot rest, a primary horizontally reciprocating carrier, side brushes operated by said carrier, an auxiliary carrier mounted on said primary carrier and movable horizontally transversely thereto, toe brushes carried by said auxiliary carrier, and a cam arranged to move said auxiliary carrier periodically transversely on the primary carrier.

4. In a shoe polishing machine, the combination of a foot rest, a reciprocating carrier, a plurality of toe brushes, an auxiliary carrier therefor mounted to move transversely on the primary carrier, and automatic mechanism for moving said auxiliary carrier transversely on the main carrier, said mechanism being actuated by reciprocation of the main carrier.

5. In a shoe polishing machine, the combination of a foot rest, a primary horizontally reciprocating carrier, a plurality of toe brushes, an auxiliary carrier therefor mounted to move transversely on the main carrier, and a cam actuated on the return stroke of the main carrier and arranged to move said auxiliary carrier stepwise transversely of the main carrier.

40 6. In a shoe polishing machine, the combination of a foot rest, a main horizontally reciprocating carrier, a plurality of toe brushes, an auxiliary carrier therefor mounted to move transversely of the main carrier, cam mechanism arranged to move said auxiliary carrier stepwise on the main carrier, and a spring arranged to return said auxiliary carrier to normal position.

7. In a shoe polishing machine, the combination of a foot rest, a main horizontally reciprocating carrier, a gear carried thereby and having a splined connection with a driven shaft, an auxiliary carrier mounted on the main carrier and movable transversely thereof, mechanism arranged to move said auxiliary carrier stepwise on said main carrier, rotary toe brushes mounted in said auxiliary carrier, and mechanism for rotating said toe brushes from the aforesaid 55 named gear.

8. In a shoe polishing machine, the combination of a foot rest, a main horizontally reciprocating carrier, an auxiliary carrier

mounted to move horizontally and transversely on the main carrier, mechanism arranged to move said auxiliary carrier stepwise on the main carrier, said auxiliary carrier being also mounted to oscillate vertically, a plurality of toe brushes, a splined rotatable shaft mounted in said carrier and 65 on which said brushes are mounted, a gear carried by the main carrier and having a splined connection with a driving shaft, and gearing connecting said gear to the splined shaft in the auxiliary carrier.

9. In a shoe polishing machine, the combination of a foot rest, a main carrier arranged to reciprocate longitudinally in line with the foot rest, an auxiliary carrier mounted to move transversely on the main 70 carrier, a plurality of brushes thereon, means for moving the auxiliary carrier step by step, comprising a wheel on the main carrier having projections thereon, means on the frame for engaging the projections and 75 rotating the wheel, means for preventing reverse rotation of the wheel and means on the wheel for engaging the auxiliary carriage.

10. In a shoe polishing machine, the combination of a foot rest, a main carrier arranged to reciprocate longitudinally in line with the foot rest, an auxiliary carrier mounted to move transversely on the main carrier, a plurality of brushes thereon, means 80 for moving the auxiliary carrier step by step, comprising a wheel, means for rotating same step by step, a roller on the wheel 85 for engaging the auxiliary carrier and moving the same and a segment on the wheel 100 for engaging the carrier and holding the same and means for returning the auxiliary carrier to initial position.

11. In a shoe polishing machine, the combination of a foot rest, a main carrier arranged to reciprocate longitudinally in line with the foot rest, an auxiliary carrier mounted to move transversely on the main carrier, a plurality of brushes thereon, means for moving the auxiliary carrier step by 105 step, comprising a wheel on the auxiliary carrier, means controlled by the reciprocation on the main carrier for rotating the wheel step by step, means on the wheel for engaging the auxiliary carrier to move the 110 latter, a spring for returning the auxiliary carrier to initial position and a segment on the wheel so arranged as to prevent return of the auxiliary carrier through a plurality of reciprocations of the main carrier.

In testimony whereof, I have hereunto set my hand.

ANDREW A. COOK.
